DRILL SUPPORT

Application filed February 25, 1929. Serial No. 342,473.

My invention relates to drill supports and more particularly to those for holding a pneumatic drill in position to operate upon rock and coal, etc.

An object of the invention is to provide a support which is adjustable vertically and about a vertical axis so that the drill can be readily adjusted to predetermined positions for use.

10 A further object of the invention is to provide a drill support embodying a fixed standard to be supported from the ground and a vertically adjustable support upon which the drill is removably held.

15 With the preceding and other objects and advantages in mind the invention consists in the novel combination of elements, constructions and arrangements of parts and operations to be hereinafter specifically referred to, claimed and illustrated in the accompanying drawings wherein:

Figure 1 is a perspective of my invention in operative position to support a pneumatic drill in position for use;

25 Fig. 2 is a view partly in elevation and partly in vertical section of the device;

Fig. 3 is a fragmentary end elevation of the same; and

30 Fig. 4 is a horizontal section taken on line 4—4 of Fig. 2.

Referring to the invention in detail a tubular rectangular standard or housing 5 having a tapered lower end 6 to be driven into the ground to support the standard in a vertical position, is provided.

35 A horizontally disposed saddle or shelf 10 is arranged above the upper end of the standard 5 and is mounted upon a rack bar 11 vertically adjustable in the standard 5. The underface of the saddle 10 is formed with a 40 depending ear 13 which is received between upstanding ears 13a formed upon the upper end of the rack bar. A bolt 14 passes through the ears 13 and 13a upon which a nut 14a is 45 threaded and cooperates with the latter in clamping the saddle in selected adjusted positions about a horizontal axis.

For the purpose of holding a pneumatic drill in a horizontal position, as disclosed in 50 Fig. 1, the saddle is provided with pairs of

upstanding transversely aligned arms 15. The arms at one side of the saddle are formed with inwardly directed laterally extending hooks or lugs 16 adapted to overlie and engage parts of the drill. The arms at the opposite side of the saddle are equipped with set screws 17 which are adjustable transversely through the upper ends of said arms and are also engageable with parts of the drill. Thus with the hooks 16 and the set screws 17 engaged with the drill the latter will be effectively held on the shelf.

For the purpose of raising and lowering the rack bar to adjust the head and saddle to the desired height a pinion 18 is arranged 55 between parallel ears 19 formed on the upper end of the standard and projects through an opening 20 in the standard to engage the rack bar. The pinion 18 is fixed to a shaft 21 which is journaled in the ears 19. A crank handle 22 is fixed to one end of this shaft for the purpose of rotating the pinion.

In order to retain the rack bar in adjusted 60 position a pawl 23 is pivoted to swing about a horizontal axis between parallel ears 24 provided on the standard opposite the ears 19. The upper end of the pawl passes through an opening 25 in the standard to engage longitudinally aligned ratchet teeth 25a formed on the adjacent face of the rack bar. An expansible coil spring 26 is inter-

75 posed between the pawl and standard to normally urge the former into engagement with the ratchet teeth. It will therefore be seen that when the rack bar is raised the pawl will engage the ratchet teeth to prevent descent of the rack bar upon release of the handle 22.

80 With my invention it will be seen that the saddle or shelf may be adjusted vertically or about a vertical axis so that the drill may operate at desired points. Moreover the drill will be held securely against longitudinal shifting in the saddle by reason of the lugs 16 and set screw 17 acting to clamp the 85 drill to the saddle.

90 What is claimed is:

In a drill support, a hollow standard, a bar longitudinally adjustable in said standard, a drill saddle rockably mounted upon 95

the upper end of said bar, said saddle having an elongated base member, pairs of upstanding arms formed at the extremities of said base, the arms upon one side of said base having laterally extending lugs for engaging one side of a drill, and the arms upon the opposite side of said base member having set screws adjustable to engage the drill upon the side opposite said lugs.

10 Signed at Christmas, in the county of Gila and State of Arizona, this 29th day of January, A. D. 1929.

HENRY W. FULLER.
